UNITED STATES PATENT OFFICE.

HARRY G. TURNER, OF CHICAGO, ILLINOIS.

CARD-FEEDING DEVICE FOR EMBOSSED-PRESSES.

1,370,169.

Specification of Letters Patent.

Patented Mar. 1, 1921.

Application filed July 17, 1920. Serial No. 396,979.

To all whom it may concern:

Be it known that I, HARRY G. TURNER, a citizen of the United States of America, and a resident of Chicago, county of Cook, and

5 State of Illinois, have invented certain new and useful Improvements in Card-Feeding Devices for Embossing-Presses, of which the following is a specification.

Die presses of the type to which this invention relates which are usually employed in the work of printing announcements, wedding invitations, etc., are found to be not well adapted for printing small cards due to the difficulty of gaging the cards 10 with respect to the printing plate or die, and the time required for doing such work. When a die press is used for printing small cards it is customary to make the impressions on cards of at least twice the final dimensions so as to prevent the cards from falling through the gage board and to enable correct placing of the cards without danger to the operator.

Even with the double sized cards, to operate the press with maximum efficiency requires two operators for controlling the press, placing and removing the cards, and there is the additional disadvantage in that each card is printed on a plurality of times 25 to use up the stock, the cards being cut apart after receiving the impressions.

The purpose of the present invention is to provide a guide whereby the cards may be fed to the press and accurately registered 30 with the printing plate in a convenient way.

A further object of the invention is to provide a suitable construction for permitting a single operator, in addition to controlling the press, to feed to the press and remove therefrom cards which are substantially the same size as the printing plate.

Another object of the invention is to provide a card guide which may be quickly adjusted for cards of different sizes.

45 These objects are accomplished by the device shown in the drawing in which—

Figure 1 is a perspective view of the improved attachment and shows the plunger of the press partly broken away.

50 Fig. 2 is a sectional view of one of the card guides taken on the line 2—2 of Fig. 1.

Fig. 3 is a similar sectional view taken on the line 3—3 of Fig. 1.

55 Fig. 4 is an enlarged sectional detail of a guide.

Briefly stated, the structure to which the

invention relates comprises a plate which is adjustably mounted on the usual gage board and has an opening similar to the opening in the gage board and through which the 60 plunger of the press passes in making an impression. Opposed grooved and flexible guides are adjustably mounted on the supporting plate and span the opening therein. Cards are fed along the grooves, the rear 65 one being used to push forward the forward cards into position for receiving the impression and out from between the plunger and bed. The guides being flexible at the point where they span the opening in the 70 gage board, permit vertical motion of the card supported therein under the action of the plunger in carrying the card against the face of the plate or die. The distance between the guides may be changed by a 75 simple adjustment and guides having grooves for receiving stock of different weights may be easily substituted one for the other.

The drawing shows the press plunger 1 in section. This plunger carries at its lower 80 end the usual counter 2 for coacting with a fixed plate or die on the bed of the press. The plunger 1 reciprocates vertically in the bearing 3.

The attachment to which this invention relates comprises a base plate 4 having slots 5 extending in the direction of length of the press whereby the plate may be adjusted in this direction with respect to the clamping means 6 for securing it to the usual gage 90 board. This adjustment carries the guide strip 7 toward or away from the plunger 1, the guide strip 7 being mounted in fixed position on plate 4. The opposite guide strip 8 has slotted arms 9 permitting the 95 shifting thereof along the plate 4 to which it is normally clamped by the thumb nuts 10. Guides 7 and 8 have grooves 11 extending along the edges of the guides adjacent the plunger 1. At the left hand end of Fig. 100 1 the guide 8 terminates in the flat un-grooved rest 12 over which the cards are successively slid into the groove of guide 7.

When a card is slid from the supply stack into first position the front and rear edges 105 of the card will come to rest on the lower plate 13 of guide 8 and on the lower plate 14 of guide 7, the forward edge of the card being below the curled-up edge 15 of the upper plate 16 of guide 7. As the card is 110 pushed along the guides its rear edge passes below the curled-up corner 17 of the upper

plate 18 of guide 8. The last card entered is always pushed to the position of the card indicated at 19; this position being regulated by the adjustable stop 20 to which the most forward card is pushed by the cards in the rear thereof. At the discharge end 21 of the guides they are curved upwardly to permit convenient removal of the cards. The parts of the guides which span the opening 22 in the plate 4 are flexible so as to freely move downwardly when engaged by the edges of the counter at the time of making an impression.

The upper members 16 and 18 are secured to the lower members of the guides by means of nuts 23 which have threaded engagement with posts 24 extending upwardly from the lower members. Springs 25 may be interposed between the nuts 23 and the guides, if it is desired to make these guides adjustable for receiving cards of different thicknesses.

In the operation of the device, plate 4 is adjusted on the gage board, the guide 8 is adjusted on plate 4, and the stop 20 is adjusted on plate 4 to cause the cards which are to be run to properly register with the plate or die which is in fixed position on the bed of the press. The cards are then fed successively into the guides, the last card pushing the forward ones ahead until stopped by the stop 20. The cards are made to easily enter the guides by sliding them over the part 12 of guide 8 and into the groove of the opposite guide. They are then pushed along the guides toward plunger 1.

The card in the last position abutting the stop is removed by raising the forward end above stop 20 and pulling the card out of

the grooves. By removing the card, it permits the feeding of another card into the opposite end of the guide.

Although but one specific embodiment of this invention is herein shown and described, it will be understood that details of the construction shown may be altered or omitted without departing from the spirit of this invention as defined by the following claims.

I claim:

1. A card feeding device for embossing presses comprising a pair of opposed grooved guides for supporting cards, said guides being flexible and mounted to span the usual opening in the gage board of the press at the location of the plunger.

2. A card feeding device for embossing presses comprising a pair of opposed grooved guides and a support therefor having an aperture at the location of the plunger on the press, said guides being flexible and spanning said aperture.

3. A card feeding device for embossing presses comprising a pair of opposed grooved guides and a support therefor having an aperture at the location of the plunger on the press, said guides being flexible and spanning said aperture, one of said guides terminating in a flat ungrooved portion.

4. A card feeding device for embossing presses comprising a pair of opposed grooved guides for supporting cards, said guides being flexible and mounted to span the usual opening in the gage board of the press at the location of the plunger, one guide being longer than the other.

Signed at Chicago this 15th day of July, 1920.

HARRY G. TURNER.
